UNITED STATES PATENT OFFICE.

JOHN S. S. FULTON, OF CHICAGO, ILLINOIS.

STOKER.

Application filed March 15, 1920. Serial No. 365,934.

To all whom it may concern:

Be it known that I, JOHN S. S. FULTON, a citizen of the United States, residing at Chicago, in the county of Cook and State 5 of Illinois, have invented certain new and useful Improvements in Stokers, of which the following is a description.

My invention belongs to that general class of devices known as stokers, and particularly to the chain or traveling grate type of mechanical stoker in which the fuel is carried from a hopper located at one end of the combustion chamber by the traveling grate. My invention has among its objects 10 the production of a device of the kind described which is simple, convenient, durable, reliable, efficient and satisfactory for use wherever found applicable. It has particularly as an object, an improved traveling grate construction and the supporting 15 and driving means for the grate. Many other objects and advantages of the construction herein shown and described will be obvious to those skilled in the art from 20 the disclosure herein made.

To this end my invention consists in the novel construction, arrangement and combination of parts herein shown and described, and more particularly pointed out in the 25 claims.

In the drawings, wherein like reference characters indicate like or corresponding parts,

Figure 1 is a vertical sectional view 35 through the rear or inner end of the grate mechanism;

Figure 2 is a sectional view taken substantially on line 2—2 of Fig. 1 or 3;

Figure 3 is a sectional view taken substantially on line 3—3 of Figure 1;

Figure 4 is a sectional view taken substantially on line 4—4 of Figure 3;

Figure 5 is a sectional view at the front end of the grate;

Figure 6 is a perspective view of one of the links for carrying and connecting the various grate units; and

Figure 7 is a sectional view taken substantially on line 7—7 of Figure 5.

The present invention is in the nature of an improvement on the stoker illustrated in my United States Letters Patent No. 1,285,671. Referring to the drawings, there is provided a stoker grate frame 8, 9, 10 and 48 of suitable size, shape and material. In the construction shown, the frame is pro-

vided with wheels 11 and mounted on tracks 12, arranged in the foundation 13 so that the stoker may be moved into and out of the combustion chamber as desired. In 60 Figures 1—4 the inner end of the stoker is shown, the outer end being illustrated in Figures 5 and 7. The frame is preferably constructed to fit between the side walls 14 of the setting, this being a detail, however, forming no part of the present invention. The stoker frame is provided with supporting rails 1 and 2, it being understood that there may be any number found necessary, this depending to a more or less extent upon the size of the stoker. However, usually at least two are desired. The rails 1 carry the traveling grate, and bars, as they carry the fuel into the furnace or combustion chamber, while the rails 2 carry 70 the returning portions of the grate.

Referring to Figure 6, there are provided the desired number of links, preferably substantially as shown in this figure, each of which consists of a body portion 16 provided with side flanges extended at 17 at one side or end, and with flanges 18 at the opposite or advancing side. It will be noted by referring to Figure 2 that the flanges 18 are spaced inwardly so that when the links are assembled two flanges 18 of one link will fit in between two flanges 17 of the other link adjacent to it at that end. Each link carries a shaft or pin 19, which connects the adjacent link to it, and I preferably mount rollers 20 at each side of the link on the shaft 19, and a roller 21 at the inside between the flanges 18—18 of the next link.

The links 16 carry I beams 22 or the equivalents, which, in the construction shown, are secured in place by brackets 23 and bolts 24. Carried by the I beams 22 are the grate bars 25 of suitable size, shape and material. In the preferred construction, the grate bars are arranged so that a bar on one link extends between two adjacent bars on the next link, etc. In other words, they interengage or intermesh so that all of the spaces are substantially closed between the bars sufficient to prevent the fuel and ashes from falling through and yet open enough to let the air through, and the grate is flexible and in addition self-cleaning, as will be hereinafter described.

The track rails 1 may be secured to the flange 27 of the frame bar 10 in any suit-

able manner, as may also the lower rail 2. It may be mentioned that the lower rail is preferably a Z bar, as indicated in Figure 3, and secured to the frame members 10 and 5 to the parts of the frame by bolts 28 or the equivalents for the purpose. In the construction illustrated, the track rails 2 are preferably braced against side strain or sagging by the clamping members 29 which 10 may be constructed with the part 30 so that it may be secured by the bolts 28 to the frame. As will be obvious, the rollers 21 traveling on the tracks 1, support the upper side of the traveling grate, while the rollers 15 20 traveling on the return tracks 2 carry the returning part of the stoker. To guide parts from one rail to the other, I arrange suitable parts at the inner end of the stoker, which parts carry the traveling grate from 20 one rail to the other and prevent its kinking or binding. While the parts just referred to may be provided by extending the rails 1 downwardly over the end of the frame and the lower rails 2 upwardly, I generally prefer 25 to provide separate parts, as shown, and terminate the track rails adjacent the frame cross bar 10 as shown. Referring particularly to Figures 1 and 4, I provide a member 33 on the outer side of the cross beam 30 10, the same being semi-circular in shape and corresponding in cross section to the rail 1, whereby the rollers 21 will follow around in the same manner as they travel on the rails 1. The parts 33 are secured in 35 place in any suitable manner, as shown, by bolts 35 extending through the cross bar 10 and part 34 of the bracket. In order to guide the rollers 20 onto their supporting bars 2 at the lower side of the grate, I provide 40 guiding members 37 which are preferably secured in place by the bolts 38 or equivalent means for the purpose on the beam 10 at each side of the member 33. As shown, the member 37 is provided with lip 45 39 engaging with the under side of the beam, and preventing any turning movement about the bolt 38. The two members 37 are made interchangeable. Each one is therefore provided with two lips 39 and two 50 bolt holes. The members 37 are each provided with a flange 40 which corresponds to the track 2 and engages the rollers 20 and guides them on to the track 2 without any break. It is believed that the operation will 55 be obvious. As the traveling grate moves, the rollers 21 follow down on the part 33 until the weight of the grate causes the rollers 20 to engage with the flanges 40 of the parts 37. The result is that the grate travels 60 about the end from one track to the other substantially noiselessly and without jar and vibration. The ashes are dumped into the pit as the grate passes the end. The parts 33 and members 37, as shown, form 65 substantially extensions to the upper and

lower track rails. This construction may be applied to either or both ends of the frame, if so desired, and suitable driving mechanism employed in connection therewith. In the machine illustrated, however, I have 70 only employed this at the inner end of the frame.

I prefer to supply a different mechanism at the other or driving end, which is preferably the outer end of the grate. Referring 75 to Figures 5 and 7, 42 represents a frame bar corresponding with the cross beam or bar 10, the same carrying the tracks 1 and 2. The frame is provided with an extending part 48 which carries a shaft 45 extending across from side to side of the stoker. It will be noted by referring to Figure 5 that the tracks 1 and 2 are preferably extended beyond the cross beam 42 as indicated at 43 and 44, the end 43 being adjacent or slightly beyond the center of the shaft 45. The shaft 45, in the construction shown, is arranged at the outer side of the front wall 46 of the combustion chamber and hopper 47. I have shown shaft 45 arranged in a bearing 56 adjustably carried by the parts 48, 51 being a bolt or the equivalent passing through the part 49 of the frame and engaged by a nut 52. This adjustable construction permits the desired tension to be put on the traveling grate, it being understood that any equivalent may be employed for the purpose. To drive and support the grate and to carry the links and parts from the lower tracks to the upper tracks 1, I provide sprocket wheels 54 which may be locked on the shaft by keys 55 or the equivalent. As most clearly shown in Figure 7, the sprocket wheel 54 is substantially a double sprocket wheel and is arranged to engage and carry the rollers 20 and thereby move the grate, bringing the bars on the lower side up to the top and under the hopper to receive the fuel and carry the same into the combustion chamber. It 100 will be particularly noted that this style of sprocket wheel is exceedingly simple and that by engaging and carrying the rollers there is practically little if any friction between the parts. The result is that while 105 the drive is positive and simple, the same operates in a very efficient manner. The shaft 45 may be driven in any suitable manner, not necessary to describe herein. 110 It will be noted that with the two ends of 115 the stoker constructed as shown and described, there is no lubrication necessary at the inner end of the stoker, as would be the case were there a rotating shaft, bearings and sprocket wheels and like mechanism for carrying the chain from the upper to the lower track. At the sprocket wheel end, in this case the drive shaft, the sprocket mechanisms are without the combustion chamber, 120 and there is not much chance for dust and 125 130

grit to get in the bearings as there would be at the inner side. It will be also noted that with the type of chain and grate bar and supporting bars therefor illustrated, the 5 grate bars are substantially self-cleaning, that is to say, (see Figure 1, as well as Figure 5) as the grates travel from the upper to the lower or from the lower to the upper tracks, they tend to wipe or shear off any 10 parts of fuel that may stick to the adjacent grate bars.

Having thus described my invention, it is obvious that various immaterial modifications may be made in the same without departing 15 from the spirit of my invention; hence I do not wish to be understood as limiting myself to the exact form, construction, arrangement and combination of parts herein shown and described or uses mentioned.

20 What I claim as new and desire to secure by Letters Patent is:

1. In an automatic stoker, a frame, upper and lower guide tracks carried by said frame, endless chains made up of a plurality 25 of links, fuel supporting mechanism mounted thereon, two sets of supporting rollers carried by each of said chains, one set of rollers operating on the upper guide tracks and the other set of rollers operating on the 30 lower guide tracks, and means mounted on said frame arranged to cooperate with the first mentioned rollers and the second mentioned rollers for carrying links and rollers from the upper to the lower guide tracks.

35 2. In an automatic stoker, a frame, upper and lower guide tracks carried by said frame, endless chains made up of a plurality 40 of links, fuel supporting mechanism mounted thereon, two sets of supporting rollers carried by each of said chains, one set of rollers operating on the upper guide tracks and the other set of rollers operating in the lower guide tracks, and track extensions mounted on said frame arranged to 45 cooperate successively with the first mentioned rollers and the second mentioned rollers for carrying links and rollers from the upper to the lower guide tracks.

3. In an automatic stoker, a frame, upper

and lower guide tracks carried by said 50 frame, endless chains made up of a plurality of links, fuel supporting mechanism carried by said links, two sets of supporting rollers carried by each of said chains, one set of rollers operating on the upper guide 55 tracks, and the other set of rollers operating on the lower guide tracks, and means mounted on said frame to cooperate successively with said sets of rollers for carrying links and rollers from the upper to the lower 60 guide tracks, comprising downwardly curved track extensions from the upper tracks and upwardly curved track extensions from the lower tracks.

4. In an automatic stoker, a frame, upper 65 and lower guide tracks carried by said frame, endless chains, fuel supporting means carried thereby, each chain made up of a plurality of links, two sets of rollers carried by each of said chains, one set of rollers operating on the upper guide tracks and the other set operating on the lower guide 70 tracks, sprocket wheels for said chains arranged at one end of said frame and engaging one set of rollers and cooperating 75 guide tracks arranged at the opposite end of said frame arranged to cooperate with said two sets of rollers carried by said chains and carrying the rollers operated on the upper guide tracks until the engagement with 80 the other set of rollers arranged for operating in the lower guide tracks.

5. In a stoker, a frame, guide tracks in the upper and lower portions of said frame, the upper guide track curved downwardly 85 at one end, and the lower guide tracks curved upwardly, one at each side of and adjacent said curved end of the upper track, a plurality of connected links movably mounted on said tracks, and grate mechanism carried 90 by said links.

In testimony whereof, I have hereunto signed my name in the presence of two subscribing witnesses.

JOHN S. S. FULTON.
